UNITED STATES PATENT OFFICE.

HENRY T. ADAMS, OF CHICAGO, ILLINOIS, ASSIGNOR TO HENRY T. ADAMS MANUFACTURING COMPANY, OF CHICAGO, ILLINOIS, A CORPORATION OF ILLINOIS.

DESIGN FOR A DESK-PAD CORNER-CLIP.

60,006.

Specification for Design.

Patented Dec. 20, 1921.

Application filed July 11, 1921. Serial No. 483,983. Term of patent 14 years.

To all whom it may concern:

Be it known that I, HENRY T. ADAMS, a citizen of the United States, residing at 6796 South Chicago avenue, Chicago, county of Cook, and State of Illinois, have invented a new, original, and ornamental Design for a Desk-Pad Corner-Clip, of which the following is a specification, reference being had to the accompanying drawing, forming a part hereof.

Figure 1 is a top perspective view of a corner-clip for desk-pads formed in accordance with the new design; and Fig. 2 is a bottom perspective view of the same.

I claim:

The ornamental design for a desk-pad corner-clip, as shown.

HENRY T. ADAMS.
